UNITED STATES PATENT OFFICE.

WILLIAM T. GAGNEBIN, OF OMAHA, NEBRASKA.

CONCRETE CONSTRUCTION.

1,104,651.

Specification of Letters Patent. Patented July 21, 1914.

Application filed November 5, 1910. Serial No. 590,896.

To all whom it may concern:

Be it known that I, WILLIAM T. GAGNEBIN, a citizen of the United States, residing at Omaha, in the county of Douglas and 5 State of Nebraska, have invented new and useful Improvements in Concrete Construction, of which the following is a specification.

This invention relates to the construction 10 of concrete buildings and particularly parts of the latter, such as posts or pillars, girders, and floors which are molded within the building structure through the medium of wood forms or molding elements. Hereto- 15 fore it has been the common practice in concrete structures of this character in building the necessary wooden forms or molds, to connect the parts thereof with nails, cleats and the like, and in dismantling or dissociating the parts after the concrete has set, 20 considerable time is required and great waste of lumber ensues.

The primary object of this invention is 25 to provide simple and effective means for maintaining the association of the planks or mold boards without the use of nails or analogous fastenings and whereby the several parts of each mold may be expeditiously dissociated after the concrete has 30 become set without loss of material or lumber, and without breaking or mutilating the part molded, especially at the angular corners.

A further object of the invention is to 35 provide an organization of form or mold members for conveniently constructing pillars or posts, girders and floors of concrete material in an integral manner within a building or other inclosure, or to form concrete posts and girders integral without the 40 floor if so desired.

With these and other objects and advantages in view the invention consists in the construction and arrangement of the several 45 parts which will be more fully hereinafter described and claimed.

In the drawing: Figure 1 is a sectional elevation, partially broken away, of a molding organization embodying the features of 50 the invention. Fig. 2 is a transverse vertical section through the girder portion of the molding organization. Fig. 3 is a cross-section through the point of intersection of one of the supporting posts or pillars and 55 the girders; a portion only of the molding devices or forms being shown. Fig. 4 is a

horizontal section through the form or mold for the post or pillar. Fig. 5 illustrates in detail perspective portions of the separable fastening means for the girder form or 60 mold.

The numeral 5 designates a post or pillar mold or form and 6 a girder mold or form, there being as many posts and pillar molds or forms used as desired and having the 65 girder forms or molds radiating from the upper extremities thereof and in some instances extending from one post or pillar form or mold to another similar mold, in order to produce an integral concrete struc- 70 ture which may or may not include a floor of concrete in a manner which will be more fully hereinafter explained.

The post mold or form 5 is composed of a plurality of corner angle irons 7 and 75 boards or planks 8, the latter as shown being in pairs at each side, or in other words each wall of the mold or form 5 as illustrated embodies two boards or planks of different dimensions to accord with the size 80 of post or pillar to be produced. The number of planks or boards 8, however, is not essential, as they will be modified in accordance with the various dimensions of posts or pillars constructed. The boards 85 or planks constituting the side walls of the post mold or form, are of such width as to provide exterior corner spaces at the adjacent side edges of the boards, and the side edges of the boards or planks 8 snugly about 90 against the outer surfaces of the two angular members of each angle iron 7 adjacent to the angle of said iron, as clearly shown by Fig. 4, and said angle irons provide corner braces and supports and are connected at 95 regular intervals by cross or tie bolts or rods 9 which may be readily applied and removed, and when applied bear directly against the outer sides of the planks or boards as shown by Fig. 4. By means of 100 the disposition of the angle irons 7 as just explained, said irons may be readily removed and withdrawn when released and the boards or side walls 8 may then be easily detached without injuring the corners of the post or 105 pillar. By having the tie rods 9 closely bearing against the walls, the latter are prevented from warping and are positively held in molding positions relatively to each other. The angular members of the angle 110 irons 7 project outwardly beyond the outer surfaces of the walls 8, and the tie rods 9

directly engage said members, thereby dispensing with extra parts or structures for engagement by the tie rods.

At regular intervals throughout the length 5 of each angle iron 7, short stop or brace angles 10 are disposed and secured to the angle irons and also have bearing against the outer sides of the boards or planks to hold the boards or planks in proper position between the angle irons 7 and to prevent outward bulging or springing of the said boards or planks. The angle irons 7 near their upper terminals have angle iron knees or supports 11 adjustably secured thereto 10 for holding an open wood seat 12, the seat 12 providing a support for a girder box or mold, which will be presently explained, the angle iron knees 11 being adjustable through the medium of bolts and nuts 13 and a plurality of openings 14 in the angle members of the angle irons 7 to provide for constructing girders or beams of any depth desired. In order to accommodate the formation of posts relatively to varying distances between one floor and a ceiling or between two floors, a splice 15 will be used in connection with the lower end of the post mold or form, said splice consisting of angle irons similar to the irons 7 and connected by tie bolts or rods in the same manner. The parts of the post or pillar form or mold as thus described may be readily associated and dissociated without requiring the use of nails or wasting lumber and providing for the repeated use of the boards or planks constituting the walls of the molds or forms and also the repeated use of the angle irons 7 at the corners of the post or pillar mold or form.

The girder molds or forms are arranged to 40 intersect the upper extremity of the post or pillar mold or form and each comprises a bottom board 16 and side boards 17 adjoining the bottom board 16 at right angles. The side boards or wall members 17 have 45 channel iron standards 18 secured thereto at intervals and each formed with an upper seat 19 and a lower angular foot 20. In the seats 19 of the standards 18 angle iron joist supports 21 are secured, and thereon joists 22 are 50 removably disposed for holding floor forms or boards 23, the ends of the joists fitting in the angle iron joist supports 21 over the upper seats 19 of the standards 18, as clearly shown by Fig. 2. The joists 22 will extend 55 from the angle iron seats or supports 21 to corresponding angle iron supports of other girder or beam molds or forms in accordance with the extent of the floor area which it is desired to produce. The side boards or 60 walls 17 of the girder or beam molds or forms are connected and supported by tie means, one of which is shown in Fig. 1 in the form of a tie rod 24 having thereon a pipe spreader 25 to prevent inward collapse 65 of the said side boards or walls 17. This

form of tie means including the spreader 25 will be introduced only at the ends of the girder.

To give depth to the girder or beam molds the latter are provided with supplemental side boards or walls 26 disposed edgewise on the upper edges of the side boards or walls 17, the joints 27 between the walls 17 and 26 being covered by the angle iron supports 21 and the said walls 26 are partially supported by the upwardly projecting members of the said angle iron supports. The side walls or boards 26 are positively held in removable position relatively to the side boards or walls 17, but are maintained in fixed position when applied by clamping dogs 28 engaging the same at intervals and having upper spiked ends temporarily driven into the outer sides of the boards or walls 26, as at 29, and lower angular ends 30 which are engaged with the upper portions of the standards 18, as shown by Figs. 1 and 2. As many of the dogs 28 will be used as may be found necessary throughout the length of the girder or beam mold. The girder or beam molds have their inner extremities projected inwardly between the flanges of the corner angle irons 7 which are extended upwardly high enough to receive the said molds and at distances from the post or pillar mold 5 the girder or beam molds 6 have posts 31 disposed thereunder at regular intervals and centrally engaging at their upper ends a bottom supporting channel iron 32 extending transversely across and in contact with the bottom boards 16 and lower edges of the side boards or walls 17 and also under the feet 20 of the standards 18. At the angles of intersection of the feet 20 with the main bodies of the standards 18 loops are movably attached and indicated by the numeral 33, said loops being of such dimensions as to embrace and adjustably engage the bottom supporting channel iron or cross-head 32 on the post 31. The loops 33 are forced inwardly when in locking position and caused to engage notches 34 cut in the under edges of the supporting iron or cross-head 32 and operate to maintain the standards 18 and side boards or walls 17 in close engagement with and in upright position relative to the bottom boards 16. By this means a girder or beam mold that may be readily assembled and dissociated without waste of material or injury to any of the parts thereof is provided, and when the parts of the mold are assembled they are firmly held in operative position by the fastening means or dogs 28 and the fastening means or clamping loops 33 and supporting iron or cross-head 32.

If it is desired to form posts or pillars and girders or beams integral therewith from concrete or analogous material without producing a floor slab as at 35, such

molding operation may be accomplished without the use of the boards 23 and by simply filling the girder or beam molds and the portion of the post or pillar mold with 5 which they intersect flush with the upper edges of said molds. In producing an integral floor slab or in forming the slab 35 integral with the posts and girders or beams, the floor boards 23 are arranged over 10 the joists 22 and the concrete or other analogous material is spread thereover in any suitable or desirable thickness, as shown by Fig. 2 in full lines and indicated by dotted lines in Fig. 1. In any event subsequent to 15 the completion of the molding operation or after the concrete has become set, the posts 31 are removed and also the girder or beam molds from the completed girders or beams, and the parts of the mold 5 are separated 20 and withdrawn from the completed post or pillar. The parts of the several molds or forms may then be again set up or reused, and when not in use they may be stored in compact form.

25 What is claimed as new is:

1. In means for molding concrete structures, the combination of inclosing walls having exterior corner spaces, main angle irons having their angles set into said corner spaces of the walls and the angular members thereof projected outwardly beyond the outer surfaces of the walls, the side edges of the walls abutting against the angular members near the angles of the 35 angle irons and having brace angles secured thereto at intervals to bear against the outer sides of the walls, and cross ties removably engaging the angular members of the main angle irons and directly bearing against and 40 extending across the outer surfaces of the walls.

2. In means for molding concrete structures, the combination of inclosing walls having exterior corner spaces, main angle irons having their angles set into said corner spaces of the walls and the angular members thereof projected outwardly beyond the outer surfaces of the walls, the side edges of the walls abutting against the 45 angular members near the angles of the angle irons, the intersecting angular members of the irons being materially greater in 50 width than the thickness of the inclosing

walls and having openings therein coincident with the outer surfaces of the walls, 55 and cross ties removably engaging the said openings of the angular members of the main angle irons and directly bearing against and extending across the outer surfaces of the walls.

3. In means for molding concrete structures, the combination of inclosing walls having engaging side edges, angle irons having the angles thereof set in the outer corners of the walls, the edges of the walls 65 bearing against the angle irons, cross ties removably extending through the angle iron flanges and held against the outer sides of the inclosing walls, angle knees adjustably secured to said angle irons, an open seat 70 held in the upper portion of the walls on the knees and adjustable vertically with the knees in relation to the angle irons, and a girder mold intersecting the upper portions 75 of the angle irons and walls and bearing upon the said seat.

4. In means for molding concrete structures, the combination with side and bottom walls, of standards secured to the outer sides of the side walls and having upper and 80 lower angular extremities, auxiliary side walls disposed on the upper edges of the first named side walls, angle iron supports held in the upper angular extremities of the standards, fastening devices removably engaging the auxiliary side walls and the angle iron supports, locking means attached to the lower angular extremities of the standards, a channel iron support applied 85 to and engaging the bottom wall and lower 90 angular extremities of the standards and having locking means formed in the bottom thereof, the fastening means carried by the lower angular extremities of the standards extending over and engaging the locking 95 means in the bottom of the channel iron, and a temporary supporting post applied to the under side of the channel iron.

In testimony whereof I have hereunto set my hand in presence of two subscribing 100 witnesses.

WILLIAM T. GAGNEBIN.
